United States Patent Office

Des. 199,888
Patented Dec. 22, 1964

199,888

BLENDER

Henry A. Dewenter, 1477 Old Mill Road,
San Marino, Calif.

Filed Apr. 28, 1964, Ser. No. 79,723

Term of patent 14 years

(Cl. D89—1)

FIG. 1.

FIG. 3.

FIG. 2.

FIG. 4.

FIG. 1 is a perspective view of a blender showing my new design;

FIG. 2 is a right side elevational view thereof;

FIG. 3 is a top plan view of the blender;

FIG. 4 is a bottom plan view thereof; and

FIG. 5 is a left exploded side elevational view thereof.

I claim:

The ornamental design for a blender, as shown.
